MACHINE FOR CLEANING SPACE BANDS

Otto C. Haderer and Walter Klein, Milwaukee, Wis., assignors, by direct and mesne assignments, to The Haderer Company, a corporation of Wisconsin

Application January 27, 1937, Serial No. 122,525

1 Claim. (Cl. 51—80)

This invention relates to a machine for cleaning space bands employed on linotype machines.

One of the objects of the invention is to provide a machine of this character which is capable 5 of quickly and thoroughly cleaning the space bands and accomplishing this in such manner as to preclude any injury thereto.

Another object of the invention is to provide a machine having these advantages and capacities and which automatically adapts itself for 10 cleaning space bands of different thicknesses.

Another object of the invention is to provide a space band cleaning machine of this character which is simple and durable in construction, advantageously combined with a motor or other 15 source of power, reliable and effective in operation, and easy and comparatively inexpensive to manufacture.

Other objects and advantages reside in certain 20 novel features of the construction, arrangement and combination of parts which will be hereininafter more fully described and particularly pointed out in the appended claim, reference being had to the accompanying drawings forming 25 a part of this specification, and in which:

Figure 1 is a view in transverse vertical section taken on line 1—1 of Figure 2;

Figure 2 is a view in longitudinal vertical section taken on line 2—2 of Figure 1;

Figure 3 is a view in transverse vertical section taken on line 3—3 of Figure 2, with parts being broken away for the sake of illustration;

Figure 4 is a fragmentary sectional view taken on line 4—4 of Figure 3;

Figure 5 is a fragmentary view in horizontal section taken on line 5—5 of Figure 1; and

Figure 6 is a view in transverse vertical section taken on line 6—6 of Figure 5.

Referring to the drawings, the numeral 1 40 designates a base with which one section 2 of a housing designated generally at H may be cast integral. The other section 3 of the housing designated at 3 is in the nature of a cover and has an inturned flange 4 abutting a similar flange 5 provided on the housing section 2. Bolts 6 are threadedly connected to the housing section 2 as indicated at 7. These bolts project through openings 8 provided in the cover section 3 of the housing and are threadedly engaged with nuts 9 which bear against the margins of the 45 openings 8 to secure the cover section 3 to the housing section 2. The nuts 9 may be provided with handles 10 to facilitate their application or removal.

A pair of cleaning rolls designated at 11 and 55 12 are disposed in the cover section of the housing. These rolls may be constituted of hard wood, felt, or other suitable composition or material, and are fixedly secured to shafts 13 and 14, respectively. Where the rolls are made of

hard wood their hub portions are provided with slots 15 at one side into which pins 16 fixed in the shafts and projecting therebeyond are fitted to constrain the rolls to rotate with the shafts. If the rollers are constructed of felt their hubs 5 are constituted of metal sleeves fixedly interconnected with the body portions of the rolls and similarly slotted to receive similar driving pins fixed to the shafts. To hold the rolls against displacement off the ends of the shafts 10 retaining washers 17 are provided and are fastened to the ends of the shafts by countersunk screws 18. The peripheral portions of these washers overlap rabbeted portions of the rolls.

The shaft 14 is supported for rotation about a 15 fixed axis and for this purpose is journaled in bearing bushings 19 and 20 supported in a fixed bearing structure 21 provided therefor on the housing section 2 (see Figure 2). A collar 22, pinned as at 23 to the rearward end of the 20 shaft 14, prevents axial movement thereof in one direction.

In between the bearing bushing 19 and the 25 cleaning roll 12 a gear wheel 24 is keyed to the shaft 14 as at 24'. A washer 25 may be provided between the gear wheel 24 and the cleaning roll 12.

The gear wheel 24 is driven by means of a drive pinion 26 keyed to the outer end of a drive shaft 27 journaled in suitable bearings 30 provided therefor on the housing and coupled as at 28 to the armature shaft of an electric motor 30. The electric motor 30 may be conveniently bolted as at 31 to the base 1.

The cleaning roll 11 is supported for rotation 35 and also for bodily movement toward and away from the cleaning roll 12 so that the machine is adapted for cleaning space bands of different thicknesses. In order to so support the cleaning roll 11 and also insure its positive drive in its various positions, it is mounted and driven in a manner which will now be described.

The rearward portion of the shaft 13 is rotatably supported in a sleeve-like bearing structure 35 of a swingable bearing bracket assembly 45 designated generally at 36. A collar 33 pinned to the rearward end of shaft 35 as illustrated at 34 prevents axial movement of said shaft 13 relative to bearing sleeve 35 in one direction. The bearing sleeve 35 is provided at its inner end with an outwardly projecting annular flange 37 which is fastened by means of screws 38 (see Figures 2 and 3) to a carrier plate 39. The plate 39 has a circular body portion provided with an integral tapered projection 40 which has an opening 40' in which one end of a shaft 41 is fitted whereby the carrier plate is rotatable or swingable relative to the shaft 13. This shaft 41 is supported for rotation in a bearing sleeve 42 which may be cast integral with the housing 50

section 2 and which constrains the shaft 41 to rotation about a fixed axis. A collar 43 pinned as at 44 to one end of the shaft prevents axial movement thereof in one direction. To the opposite end of the shaft an idler pinion 45 is fixed as, for example, by means of a stud bolt 46 which extends through the central opening of the pinion and is threadedly connected with the shaft 41 as indicated at 47. The pinion 45 and collar 43 preclude axial movement of the shaft 41 in either direction and the pinion 45 and adjacent end of bearing sleeve 42 constrain the bracket assembly 36 to swinging movement about shaft 41 as an axis. The pinion 45 meshes with a gear wheel 48 keyed as at 48' to the shaft 13 and interposed between the carrier plate 39 and a washer 50, the washer 50 in turn being interposed between one face of the gear wheel 48 and the cleaning roll 11. The idler pinion 40 not only meshes with the gear wheel 48 but also with the drive pinion 26 as shown in Figure 3. The housing section 2 is provided with an elongated or slot-like opening 51 to provide the clearance necessary to accommodate the bodily movement of the bearing sleeve 35.

With this construction, the drive pinion 26 not only drives the gear wheel 24 and its shaft 14 but also the idler pinion 45 which, in turn, rotates the gear wheel 48 and consequently the shaft 13. The bearing bracket 36 so supports the gear wheel 48 and the cleaning roll 11 that if the cleaning roll 11 moves toward or away from the roll 12 to accommodate space bands of various thicknesses, the gear wheel 48 will roll 35 around the idler pinion 45 so that the transmission of the drive to the gear wheel 48 and cleaning roller 11 will not be impaired in the various relative positions of their parts. This action is due to the mounting of the bearing bracket 36 for swinging movement about the axis of rotation of the idler pinion 45.

For the purpose of resiliently or yieldingly pressing the cleaning roll 11 into rolling contact with the cleaning roll 12, the carrier plate 39 is provided with a socket 55 receiving one end of a compression coil spring 56. The other end of this spring fits over the reduced inner end of an adjusting screw 57 threadedly interfitted with an internally threaded bearing 58 provided on the housing and having a shoulder 59 against which one end of the spring 56 abuts. By adjusting the screw 57 the extent to which the spring 56 is compressed may be varied and as a consequence the force with which the cleaning roll 11 is pressed against the cleaning roll 12 may be varied.

The housing H and preferably the cover section 3 thereof is provided with means for feeding the space bands B to the nip of the cleaning rolls 11 and 12 and may also be provided with guide means for conveying the bands away from the rolls to a point of deposit. For this purpose the housing section 3 is provided with an opening 60 opposite the nip of the rolls and overlying a feed guide designated generally at 61. The guide-way 65 is provided with ribs 62 along its sides which define a restricted throat or entrance-way 63 to the guide. Inwardly of the wall of the housing and adjacent the nip of the rolls these ribs are cut away as at 64 to enlarge the guide-way and adapt it to allow the head of the space band to drop thereinto. The space band is designated generally at B and has a shank s and the conventional head b interfitted with the shank in the usual way. When a space band is to be cleaned its

head is slid along the top of the rib 62 until it overlies the cut-away portion 64 of the guides. The space band then drops down so that the side edges of its shank s are slidably interfitted with the inner faces of the guide ribs 62. In this way the space band is constrained against any twisting or lateral displacement with its head and is engaged and gripped by the cleaning rolls. Any twisting or distortion thereof is effectively prevented. During its passage through the rolls 10 the head of the band is cleaned of any deposits of lead or foreign matter and this may result simply from its passage between the rolls or by the operator pulling backward on the band intermittently as it is gripped and acted upon by the rolls. On the opposite side of the rolls from the feed guide an ejecting guide-way 65 is provided and consists simply of a shelf 66 and side walls 67 to insure the passage of the band out through the discharge opening 68.

Opposite the ejection guide 65 is a deflector strip 70 and a hanger strip 71. These strips are releasably secured in a mounting bracket 72 supported on the housing H by means of wing nuts 73 and 74, respectively, and their position may be accurately determined by gauge collars 75 and 76 releasably secured to the strips by set screws 77 and 78, respectively. The deflector strip 70 has a downwardly inclined portion 80 which engages the heads of the space bands to deflect them down onto the upwardly inclined end portions 81 of the hanger strip 71. The space bands then slide down the strip 71 to the position shown in dotted lines. Obviously, other means may be provided for receiving or stacking the strips after they have passed through the machine.

In the use of the device a suitable quantity of graphite is provided in the cover section of the housing to augment the cleaning action of the surfaces of the rolls. When the operator releases a space band gripped between the rolls the rolls will carry the band through their nip at an increased speed and out through the ejection guide of the housing. As they are projected from the ejection guide they engage the deflector strip 70 and the upwardly inclined portions 81 of the hanger strip 71 enter the slots of the space band which then slide down the inclined hanger strip to the position shown in dotted lines.

While we have shown and described one construction in which the invention may be advantageously embodied, it is to be understood that this construction has been selected merely for the purpose of illustration or example, and that various changes in the size, shape and arrangement of the parts may be made without departing from the spirit of the invention or the scope of the subjoined claim.

The invention claimed is:

A machine of the character described comprising a housing having two sections, shafts journaled in one of said sections and having unsupported projecting portions, gears on said shafts, gear means for rotatably driving said shafts, and cleaning rolls on said projecting portions, said cleaning rolls being positioned within the other of said sections and adapted to engage and clean space bands fed thereto, said last mentioned section having integrally formed thereon guideways for conducting space bands to and from the nip of said rolls.
